(No Model.)

C. A. BELL.
DRILLING MACHINE.

No. 431,319.

Patented July 1, 1890.

UNITED STATES PATENT OFFICE.

CHARLES ALEXANDER BELL, OF GLEN WILTON, VIRGINIA.

DRILLING-MACHINE.

SPECIFICATION forming part of Letters Patent No. 431,319, dated July 1, 1890.

Application filed April 1, 1890. Serial No. 346,208. (No model.)

To all whom it may concern:

Be it known that I, CHARLES ALEXANDER BELL, a citizen of the United States, residing at Glen Wilton, in the county of Botetourt 5 and State of Virginia, have invented certain new and useful Improvements in Drilling-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention has relation to drilling-machines which are designed more especially to be operated by hand-power; and it consists in the novel construction and combination of parts, all as hereinafter set forth.

20 In the accompanying drawings, in which Figure 1 is an end view; Fig. 2, a front elevation; and Figs. 3 and 4 are details, I have illustrated the drilling-machine having a base portion A, to which are connected three uprights B B, which are secured together by the transverse braces C C to form a frame-work capable of a limited adjustment upon the base to which the uprights are connected 25 preferably by screw-pivots in such a manner 30 that the frame may be secured in its adjusted position.

On one side of the frame are two of the uprights B B in approximate position and having between them an interval for the gear-wheels D D', whereof the former is provided 35 with a crank d and the latter with a horizontal crank-shaft e, which extends across the frame and is provided with the crank bends a a at the sides of its middle portion to receive the lower ends of the pitman straps 40 or rods b b, the upper ends of which are connected to staples f f of the sliding cross-head F and have a limited play on said staples. This cross-head is provided with reduced ends

45 which bear in the vertical slots of the lateral posts or uprights B B and has reciprocating motion thereon when the machine is in operation. On the shaft e at the sides of the pitman straps or rods b b are rigidly secured 50 the fly-wheels G G, these fly-wheels being ar-

ranged in position with relation to said straps or rods and with relation to the middle portion of the frame where the vertical drill-rod L is located. This drill-rod is preferably square in cross-section. A spring S, above a 55 bearing through the cross-head F, is secured or connected to the drill-rod, being fixed thereto by means of a suitable collar and set-screw, which may be loosened to allow adjustment of the drill as the work proceeds. 60 The lower portion of the drill-rod passes through the bearing in a lower transverse brace-bar of the frame.

Z indicates a star-collar or pointed collar having the radiating angular projections z. 65 This collar is provided with a square opening which fits the drill-rod loosely, so that the latter can move up and down readily through said opening.

The collar Z rests on the middle portion of 70 the transverse crank-shaft e, which is provided with a suitable projecting pin or stud v, which at each revolution of the shaft strikes one of the radial points of the star-collar and turns the same a little, sufficiently 75 to give the drill a new angular position with relation to its cutting-edge. In this manner when the machine is operated by turning the crank-handle H the drill receives a step-by-step rotary movement while it is raised and 80 dropped by the cross-head and its spring-connection resting thereon. The lower end of the spring works against the upper transverse brace of the frame, which gives tension 85 to the spring for the downward stroke when the cross-head is raised by the crank-shaft e. This movement is rendered steady and uniform and lateral action prevented by the arrangement of the cranks, pitman-straps, and fly-wheels. 90

Having described this invention, what I claim, and desire to secure by Letters Patent, is—

The drilling-machine consisting of the supporting-frame having in one side an additional upright, the drill-rod arranged in a cross guide-bar of said frame, and passing through a sliding bar engaging vertical grooves in one side bar or piece and the additional side bar or piece of said frame, said 95 100

rod being encircled by a spring connected thereto and bearing upon said sliding bar, the crank-shaft connected by links to the latter bar and carrying a pin intermediately of its links, the star-pointed collar secured to said drill-rod and engaging said pin, and the gearing with the handle-shaft, substantially as set forth.

In testimony whereof I affix my signature in presence of two witnesses.

CHARLES ALEXANDER BELL.
